G. G. CLOUGH.

INTERNAL COMBUSTION ENGINE.

APPLICATION FILED SEPT. 10, 1913.

1,096,683.

Patented May 12, 1914.

UNITED STATES PATENT OFFICE.

GEORGE G. CLOUGH, OF GALVESTON, TEXAS.

INTERNAL-COMBUSTION ENGINE.

1,096,683.

Specification of Letters Patent. Patented May 12, 1914.

Application filed September 10, 1913. Serial No. 789,146.

To all whom it may concern:

Be it known that I, GEORGE G. CLOUGH, a citizen of the United States, residing at Galveston, in the county of Galveston and State 5 of Texas, have invented a new and useful Internal-Combustion Engine, of which the following is a specification.

The present invention relates to improvements in internal combustion engines, one 10 object of the invention, being the provision of an engine, the cylinder of which is provided with a semi-spherical upper end, for the rotatable reception of a similar shaped power cylinder carrying shell, the upper end 15 of said shell being provided with a single port for controlling the intake and exhaust ports of the engine, said shell therefore constituting a rotary valve and combined combustion and power chamber, of the engine.

20 A further object of the invention, is the provision of an internal combustion engine, the outer casing of the cylinder of which is provided with an intake and exhaust port, there being disposed within the same, to 25 form a lining therefor a rotatable shell, the upper end of which constitutes the explosion chamber, and is provided with a single port for controlling the intake and exhaust ports of the engine during the rotation of the 30 shell, there being provided means disposed exteriorly of and connected to the upper end of the shell for holding the same properly positioned relatively to the casing, and so as to permit the necessary longitudinal and 35 lateral movements of the shell, due to the expansion and contraction of the metals, wear of the said parts, and vibration of the said cylinder casing, and shell in action.

With the foregoing and other objects in 40 view which will appear as the description proceeds, the invention resides in the combination and arrangement of parts and in the details of construction hereinafter described, and claimed, it being understood that 45 changes in the precise embodiment of the invention herein disclosed can be made within the scope of what is claimed without departing from the spirit of the invention.

In the drawings—Figure 1 is a longitudinal sectional view through a four cylinder engine embodying the present invention. Fig. 2 is a cross sectional view through the first cylinder thereof and through the base beyond the gearing for operating the rotary

valve. Fig. 3 is a plan view of the combined shell and rotary valve with the port thereof in elevation.

Referring to the drawings, the numeral 1 designates the crank case and base of the engine, which has mounted therein, the 60 crank shaft 2 which has attached thereto the piston rods 3 and 4. In the present instance, the connecting rods 3 and 4 are in pairs, though the conventional crank shaft for firing the cylinders in the order 1—3—4—2—65 may be used. Connected to the connecting or piston rods 3 are the pistons 3' while connected to the rods 4 are the pistons 4'. The main cylinders 5, as shown in Fig. 1, are cast *en bloc* in the present instance, although they may be cast and formed separately. Housing all of the cylinders, as clearly shown in Figs. 1 and 2 is a casing 6, which with the top 6' constitutes a water jacket surrounding all the cylinders of the 75 engine and thus constituting a separate element, in the present instance, to be positioned over the cylinders of the engine in such manner as to be water tight and to permit of the necessary circulation of the water 80 to cool the engine.

Each casing 5 is provided with an exteriorly threaded sleeve 7 concentrically of its upper end, there being disposed thereupon the limiting lock nut 8 which coacts 85 with the upper lock nut 9 to secure the top 6' of the casing 6 in water tight relation to the sleeve 7. Each casing 5 is provided with the intake chamber 10 and the intake port 10', an intake manifold 11 being led to the 90 chamber 10 in any desired manner. At a properly ascertained opposite point of the cylinder 5, approximately 200 to 225 degrees distant from the intake port 10, is provided the exhaust chamber 12 having the exhaust 95 port 12' which has leading therefrom, the exhaust manifold 13.

The inner upper end of the casing 2, as clearly shown in Figs. 1 and 2, is formed semispherical, as at 14, and is cut away as 100 at 15 a greater part of the length of the longitudinal walls thereof, so that the semispherical end 16 of the rotary shell and valve 17 may be properly seated within the casing 5 from below so that the lower ring 105 18 will abut the lower inner wall of the casing 5 while the semi-spherical end 16 will engage the wall at 14, the intermediate por-

tion being spaced so as to reduce the friction between the parts during the rotation of the combined valve and shell 17.

One method of rotating the shell 17, includes the worm gear 20 connected to the lower end of the shell, said worm gear being positioned to mesh with the operating worm 21 mounted upon the longitudinal shaft 20 disposed within the crank case of the engine and rotating in proper time by means of the small gear 23 and the large gear 24 keyed to the crankshaft 2. Any means of combination of gears, or bevels may be employed, or the shaft 22 may be operated by chain from the crank shaft 2. In the present instance, the shell 17 is mounted to operate and rotate at half engine speed, or one rotation for every two rotations of the crank shaft 2. Each rotating valve and shell 17 is provided with a port 25 somewhat in the form of a triangle, which is adapted to, at the proper time, register with the ports 10' and 12' of its respective casing 5, and thus control the admission of the explosive charges, which constitutes the combustion and compression chamber of the engine, and also the exhaust of the burnt gases therefrom and through the manifold 13.

In order to provide a means for properly mounting the combined rotary valve and shell 17 within its casing 5, a sleeve 26 is formed integral with the upper semi-spherical end thereof, and is disposed concentrically of the shell so as to fit rotatably within the sleeve 17 of the casing 5, the bore thereof being screw threaded interiorly for the reception of the jump spark plug 27, as clearly illustrated in Figs. 1 and 2. Thus the terminals of the spark plug will be positioned within the dome of the rotary valve or shell 17 and at a point to best ignite the compressed charge therewithin. By making the ports 10', 12' and 25 relatively large, the intaking of the charge is exceedingly rapid, while the exhaust permits of the thorough scavenging and cleansing of the combustion chamber prior to the introduction of a new charge.

In order to properly mount the rotary valve and shell 17 so as to permit of the necessary vertical and longitudinal movement thereof, due to the expansion and contraction of the contacting metals, and the wear thereof through use, and also due to the vibration of the parts through action of the engine in operation, a resilient washer 28 is connected to the sleeve or upper end 26 of the shell 27 and rotates therewith, the under side thereof adjacent the periphery being disposed to rest upon the ring 29 which is supported by means of balls 30 to form a ball bearing at this point. In the present instance the shouldering portion 31 of the spark plug 27 holds the resilient

washer 28 properly locked upon the upper end of the sleeve 26, but is also securely fastened by screws or keys to avoid the sleeve or valve being displaced downward when the spark plugs are removed. The conduit 32 is disposed within the casing 34 carried by the water jacket 6 and having connection with the tubes 33 of the spark plug, such connections being of a character that permits the rotation of the spark plug without breaking the electrical connection with the conductors 32.

The present ignition system is merely shown as indicative of any system that will operate where the spark plugs 27 are rotated as in the present case.

From the foregoing description it is apparent that with a combined shell and rotary valve 17 constructed as herein shown, with the bearing points at the semi-spherical upper end thereof, and the similar shaped portions of the casing 5, and at the portion 18 of the shell 17 and the lower end of the casing 5, that the friction is greatly reduced, and also due to the ball and socket connection formed by the semi-spherical portions of the member 17 and casing 5, the necessary movement is permitted to the shell 17 due to the expansion and contraction of the connecting metals, the wear of the connecting metals due to use, and the movement of the parts due to the vibration of the engine in action.

What is claimed is:

1. An internal combustion engine, including a power cylinder having a chamber, the upper end of which is semi-spherical and provided with an intake and an exhaust port, a shell of similar shape to the chamber mounted therein for rotation with its semi-spherical end and its lower end only in contact with the walls of the chamber, said shell having a single port for controlling the ports of the chamber, a power piston mounted for reciprocation within the shell, a crank shaft, a connecting rod connecting the piston to a crank shaft, and means operably connecting the shell to the crank shaft.
2. An internal combustion engine, including a power cylinder having a chamber, the upper end of which is semi-spherical and provided with an intake and exhaust port, a shell of similar shape to the chamber mounted therein for rotation and having a single port for controlling the ports of the chamber, a greater portion of the exterior wall of the shell and the adjacent wall of the cylinder being out of contact, a power piston mounted for reciprocation within the shell, the shell operably connected to the crank shaft, and rotatably timed for proper registration with intake and exhaust ports by gears or drive chains and sprockets, a concentrically disposed sleeve carried by the

upper end of the cylinder in communication with the chamber, a spark plug carrying sleeve projecting from the shell and rotatably mounted in the sleeve of the cylinder, 5 and resilient means carried by the sleeve of the shell and coacting with the upper end of the cylinder to hold the shell seated within the cylinder.

3. An internal combustion engine, including a power cylinder having a chamber, the upper end of which is semi-spherical and provided with an intake and an exhaust port, a combined shell and combustion chamber insertible and rotatable within the 15 chamber of the cylinder, and having a semi-spherical upper end for contacting and forming with the upper end of the chamber, a ball and socket joint, the upper end of said shell being provided with a single port 20 for controlling the intake and exhaust ports of the cylinder and thus forming a combined combustion chamber-cylinder and valve, a power piston mounted for recipro-

cation within the shell, means operably connecting the shell to the semi-spherical end 25 and the lower end of the shell forming the bearings with the cylinder for the shell, while the intermediate portion thereof is out of contact with the cylinder, a concentrically disposed sleeve carried by the upper end of the cylinder in communication with the chamber, a spark plug carrying sleeve projecting from the shell and rotatably mounted in the sleeve of the cylinder, 30 and resilient means carried by the sleeve of the shell-valve and coacting with the upper end of the cylinder to hold the shell seated within the cylinder.

In testimony that I claim the foregoing as my own, I have hereto affixed my signature in the presence of two witnesses.

GEORGE G. CLOUGH.

Witnesses:
